UNITED STATES PATENT OFFICE

THOMAS F. MOORE, OF MORRIS PLAINS, NEW JERSEY

WELL POINT

Application filed October 17, 1927. Serial No. 226,689.

- This invention relates to an improved device, technically known as a well-point for draining water-containing soil of the class set forth in my pending applications Serial 5 No. 59,318, filed September 29, 1925, and formally allowed April 29, 1927, Patent 1,648, 55 587, Nov. 8, 1927, and Serial No. 71,148, filed November 24, 1925, and formally allowed July 15, 1927, Patent 1,657,684, Jan. 31, 10 1928, in which the main object is to permit the same device to be used for jetting a hole in the soil by water under pressure to facilitate the sinking of the well point into the hole and when sunk to the proper depth in 15 the moisture-containing soil for withdrawing the moisture therefrom by suction until the surrounding soil is sufficiently dry to permit excavation for constructive work therein.
- 20 Devices of this character are necessarily subjected to rough and severe usage in penetrating different kinds of soil which frequently exist in strata of different depths and sometimes require more or less churning action of the well-point to enable it to be sunk to the proper depth for receiving the water-seepage in the soil and one of the specific objects of the present invention is to construct the device so that its cross sectional 25 30 area above the valve chamber or driving point will be substantially equal throughout its length so that it may be raised and lowered in the soil with a minimum resistance due to contact of the soil with the exterior surface of the device.
- 35 Another object is to assemble the various parts of the device in such manner as to avoid shearing strains upon the connections between them.
- 40 Another object is to assemble the pipe and its wood backing upon each other and upon the valve case or driving point in such manner that the outer surfaces of the pipe and wood backing will come within the cross 45 50 sectional area of the valve case and thereby to avoid excessive external projections which might interfere with the free practical working of the device as a whole into and out of the soil.
- 55 A further object is to assemble the pipe 50 55 60 65 70 75 80 85 90 95 100
- and wood backing around the axis of the valve case and to provide said wood backing with external lengthwise channels communicating with the interior of the valve chamber for permitting the seepage water to drain into said valve chamber, the pipe and wood backing being preferably surrounded by a wire screen to exclude solid material without interfering with the free flow of the seepage water through said channels and into the valve chamber.
- 60 Other objects and uses relating to specific parts of the device will be brought out in the following description.
- In the drawings:—
- 65 Figure 1 is a side elevation of a well-point embodying the various features of my invention.
- 70 Figure 2 is an enlarged vertical sectional view of the same device partly in elevation and partly in section and also partly broken away in which the lower valve case is floated against its seat.
- 75 Figure 3 is a detail vertical sectional view through the lower portion of the device taken in the plane of line 3—3, Figure 2.
- 80 Figures 4, 5 and 6 are transverse sectional views taken respectively in the planes of line 4—4, Figure 3, and 5—5, and 6—6, Figure 2.
- 85 As illustrated, this device comprises a valve case section —1—, a pipe section —2—, a back section —3— of wood and a wire screen section —4— together with suitable means including a clamping plate —5— for clamping the edges of the screen to the wood section —3— and float valves —6— and —7— controlling the port in the valve case in a manner hereinafter more fully described.
- 90 The valve case —1— is preferably composed of hollow sections —8— and —9— of steel or equivalent hard metal secured one within the other by means of a coupling pin or rivet —10—, the upper end of the section —8— being made in the form of a regular polygon in cross section while the lower end is tapered downwardly and circular in cross section for receiving the upper end of the section —9—.
- 95 That is, the upper end of the section —9— is tapered upwardly and is telescopically 100

fitted within the lower end of the section —8— to form a liquid-tight joint therewith while its lower end is tapered downwardly to form a discharge nozzle for the water 5 which may be introduced under pressure through the pipe —2— into the valve chamber as —8'— of the section —8— for the purpose of jetting a hole in the soil and thereby 10 facilitating the downward movement or sinking of the device into the soil.

In order that the water under pressure may flow into the interior of the nozzle —9— the upper end wall of said nozzle is provided with a port —11— controlled by the float 15 valve —6— which opens downwardly but is held against downward displacement into the mouth of the nozzle by engagement with the cross pin —10— as shown by dotted lines in Figure 1.

20 The upper end of the valve case section —8— is provided with a transverse partition —12— some distance above the top wall of the nozzle section —9— and having a port —13— which is controlled by the float valve 25 —7—.

One side of the upper end of the section —8— and transverse partition —12— is provided with a substantially semicircular cut-out or recess for receiving the lower end of 30 the pipe section —2— which is welded or otherwise secured to the walls of the recess to form a rigid water-tight connection between the pipe and valve case.

The lower end of the pipe —2— is seated 35 directly upon the lower wall of the recess, the meeting edges of those parts being provided respectively with a V-shaped tongue and a V-shaped groove as indicated at —14—, Figure 2, to facilitate welding at this joint 40 and also to assist in holding the pipe and valve against relative lateral movement.

When the pipe —2— and valve case —1— are assembled in the manner just described the outer face of the pipe forms a circumferential continuation of the upper end of 45 of the valve case and lies approximately within a circumscribed circle around the upper end of said case but at one side of the axis thereof as shown more clearly in Figure 2.

50 The pipe —2— may extend upwardly to any suitable height according to the depth to which the device is to be inserted into the soil for drainage purposes and is provided with a series of rearwardly projecting internally-threaded nipples —15— welded or otherwise permanently secured thereto in longitudinally spaced relation for receiving a corresponding number of clamping bolts 55 —16— by which the wooden section —3— 60 and pipe section —2— are secured to each other.

This wooden backing section —3— extends upwardly from the valve case —1— the major portion of the length of the pipe —2— 65 mainly within the cross sectional area of the

upper end of the valve case section and is provided with a substantially semi-circular lengthwise groove —17— in which the adjacent side of the pipe is seated so that the walls of the groove may assist in holding the 70 pipe —2— and wooden backing —3— in parallel relation or against relative lateral movement transversely of the axes of the bolts —16—.

The upper end of the case section —8— is 75 provided with a marginal flange —17— projecting some distance above the transverse partition —12— to form a chamber —18— for receiving seepage water and permitting the same to pass through the registering port 80 —13— and thence into the valve chamber —8'— from which it may be withdrawn by suction through the pipe —2—.

The lower end of the wooden section —3— is reduced and snugly fitted in the upper end 85 of the valve case section —8— within the flange —17— but terminates a short distance above the partition —12— to avoid closing of the chamber —18— and port —13—.

This wooden backing section —3— is provided with a plurality of, in this instance four, lengthwise channels —19— arranged in uniformly spaced relation circumferentially in the perimeter thereof and extending upwardly from the lower end of said section 95 the major portion of its length and communicating at their lower ends with the chamber —18— to allow seepage water from the soil to flow through said channels at any level throughout the length thereof and thence 100 into the chamber —18— and —8'— to be drawn outwardly by suction through the pipe —2—.

The upper portion of the wooden backing section —3— above the channels —19— is 105 made in the form of a regular polygon transversely except as to the semi-circular groove —17— to conform more closely to the shape and size of the upper end of the valve case section —8—.

The screen —4— is wrapped around the outer faces of the pipe —2— and wooden backing —3— and also around the perimeter of the flange —17— to extend upwardly from said flange slightly above the level of 110 the upper ends of the channels —19—, the opposite longitudinal edges of the wire screen being overlapped against the back of the wooden section —3— and secured in place by the clamping plate —5— and suitable clamping screws —20— which serve to hold the clamping plate and screen in fixed relation to the pipe section —2— and backing section —3—.

The lower end of said clamping plate —2— 125 is also secured by an additional screw —20'— to the periphery of the upper end of the valve case section —8— to assist in holding the backing section —3— and valve case section against relative endwise movement.

It is now evident that the well-point as a whole is of approximately uniform cross sectional area from the bottom of the pipe —2— to the top of the wooden backing —3— 5 and that those parts are arranged circumferentially about the axis of the valve case —1—, the lower section —9— of which is tapered and hardened to resist wear but may be removed when necessary for replacement by 10 simply removing the pin —10—, it being understood that the screen —4— and clamping plate —5— are sufficiently thin to avoid any appreciable resistance to the vertical movement of the device in the soil. 15 The valve case sections —8— and —9— constitute a cage for the valves —6— and —7— while the projection of the lower end of the pipe —2— below the partition —12— forms with the opposed wall of the section 20 —8— a guide chamber for holding the valve —7— in alignment with its port.

Operation

In using the device for withdrawing moisture from the soil it is placed in an upright position with its nozzle —9— in the soil and if the latter is sufficiently soft the device may be forced downwardly by hand or other means to the required depth for removing 25 the moisture from the soil or if the soil is more or less hard water under pressure may be forced through the pipe —2— through the top downwardly thereby opening the float valve —6— and allowing the water to pass 30 from the tapered nozzle —9— into the soil for jetting a hole therein and incidentally moistening the surrounding soil to facilitate the entrance of the device into the hole thus formed. 35 This operation may be continued until the well-point is sunk to the required depth for withdrawing the moisture therefrom at which time the upper end of the pipe —2— will be disconnected from the water pressure 40 supply and reconnected to a suitable suction pump not shown for creating suction in the pipe from the bottom upwardly or from the chamber —8'— through said pipe.

This suction in the chamber —8'— and 45 pipe —2— will cause the closing of the valve —6— in the upper end of the nozzle —9— and at the same time will open the valve —7— which controls the port —13— thereby allowing the water in the soil to pass through 50 the screen —4— and thence downwardly through the channels —19— into the valve chamber —8'— from which it will be drawn by suction upwardly through the pipe —2— or through suitable conduits connected there- 55 with to any locality remote from the place of installation of the well-point, this operation being continued until the soil in the vicinity of the well-point is sufficiently dry 60 to permit excavation of the soil for constructive work in the excavation.

It is evident that the well-point may remain in operative position during the construction work in the immediate vicinity thereof so as to remove any moisture which may tend to accumulate in the excavation 70 but as soon as the construction work is sufficiently under way the well-point may be readily withdrawn and reinserted in some other locality where the moisture is to be removed from the soil for repeating the opera- 75 tion just described.

When water under pressure is being forced through the pipe and nozzle for jetting a hole in the soil the water entering the chamber —8'— will cause the float valve —7— to close its port —13— and at the same time cause the valve —6— to open its port —11— to allow the inflowing water under pressure to pass through the tapered portion —9— and into the underlying soil.

What I claim is:—

1. A device for draining water-containing soil comprising a pipe, a wooden backing extending lengthwise of the pipe and secured directly to the periphery thereof and provided with a lengthwise channel in its outer surface, a wire screen secured to the wooden backing across the channels and a metallic nozzle secured to corresponding ends of the pipes and wooden back and having its interior communicating with the adjacent ends of the channels for receiving the water passing therethrough, said pipe being adapted to be connected to a suction device for withdrawing the water from said chamber.

2. A soil drainage device as in claim 1 in which the wood backing is provided with a longitudinal groove in which the adjacent side of the pipe is seated.

3. A soil-drainage device as in claim 1 in which the metallic nozzle is secured by welding or equivalent fastening means to the adjacent end of the pipe.

4. A soil drainage device as in claim 1 in which the nozzle is provided with a transverse partition above the lower end of the pipe and abutting against the periphery thereof and is provided with a port therethrough and a float valve controlling said port.

5. A soil drainage device of the character described, comprising an upright valve case having a water inlet port in the top wall thereof, a self-opening valve below and controlling said port, and a combined suction and pressure pipe secured in an opening in the upper end of the valve case and communicating with the valve chamber, said valve being adapted to be opened by suction in said pipe.

6. A soil drainage device as in claim 5 in which the valve case is provided with a nozzle section extending into the valve chamber and provided with a port in its upper end, and a self-opening valve below and controlling the last-named port.

7. A soil drainage device of the character

described comprising an upright pressure and suction pipe, a valve case secured to the lower end of the pipe and provided with a tapered discharge nozzle having a port in its upper end communicating with the adjacent end of the pipe, a self-opening valve below and controlling said port, said valve case having a valve chamber extending upwardly above and at one side of the lower end of the pipe, and provided with a water inlet port, and a self-opening valve below and controlling the second-named port.

8. A soil drainage device of the character described comprising an upright pressure and suction pipe, a valve case section secured to the lower end of the pipe and provided with a valve chamber communicating with the interior of the pipe and extending upwardly beyond the lower end and at one side thereof and having its top wall provided with a water inlet port, a self-opening valve in said chamber below and controlling the port adapted to be opened by suction in the pipe, a nozzle section having its upper end extending 25 into the valve chamber and provided with a port communicating with the valve chamber, and a self-opening valve below and controlling the second-named port, and adapted to be closed by suction in said pipe.

30 9. A well-point of the character described comprising an upright pipe, a valve case secured to the lower end of the pipe and provided with a valve chamber communicating with the interior of the pipe and extending 35 upwardly at one side and above the lower end thereof and provided with a port, a valve controlling said port, a nozzle secured to the lower end of the valve case and extending into the valve chamber and having its upper end provided with a port communicating with the valve chamber, a valve controlling 40 the second-named port, a backing strip having its lower end seated on the upper end of the valve case and its remaining portions extending along the pipe and provided with a lengthwise groove in which the pipe is seated, said strip having lengthwise channels 45 therein communicating with the port in the top of the valve case, and a screen secured to 50 said strip across said channels.

In witness whereof I have hereunto set my hand this eleventh day of October, 1927.

THOMAS F. MOORE.
